UNITED STATES PATENT OFFICE.

THOMAS S. HOMANS, OF HEMPSTEAD, NEW YORK, ASSIGNOR TO INTERTYPE CORPORATION, OF NEW YORK, N. Y., A CORPORATION OF NEW YORK.

TYPOGRAPHICAL MACHINE.

1,237,043.

Specification of Letters Patent. Patented Aug. 14, 1917.

Application filed April 22, 1914. Serial No. 833,738.

To all whom it may concern:

Be it known that I, THOMAS S. HOMANS, a citizen of the United States, residing at Hempstead, in the county of Nassau and State of New York, have invented new and useful Improvements in Typographical Machines, of which the following is a specification.

The present invention relates to improvements in typographical machines and more especially to those of the linotype class wherein matrices are delivered from one or more magazines under the control of keyboard mechanism to compose a line from which a slug is cast, and after the casting operation the matrices are returned to the respective channels of the magazine or magazines. The primary object of the present invention is to provide novel and improved means for shifting a plurality of magazines to bring any one of the magazines into operative position, relatively to the matrix delivery means, as desired, and also to carry all the magazines into a position for removal.

To these and other ends, the invention consists in certain improvements, and combinations and arrangements of parts, all as will be hereinafter more fully described, the novel features being pointed out particularly in the claims at the end of the specification.

In the accompanying drawings:—

Figure 1 is a side elevation of the upper portion of a typographical machine of the well known linotype class embodying the present invention, two magazines being shown therein and the lower magazine being in operative position relatively to the keyboard-controlled matrix delivery means;

Fig. 1^a is a diagrammatic view showing the motion imparted to the magazines in shifting them to bring one or the other into operative position, relatively to the keyboard-controlled matrix delivery means, and also showing the present invention applied to a construction wherein the escapements are stationary or non-shiftable;

Fig. 2 is a view similar to Fig. 1 showing the upper magazine in operative position relatively to the escapement actuating or matrix delivery means;

Fig. 3 is a view similar to Fig. 2 showing the channel entrance in inoperative position relatively to the matrix delivery means, and

also showing by the dotted lines the magazines in position for removal;

Fig. 4 is a detail perspective view showing means for connecting and disconnecting the operating lever or member with respect to the magazine shifting means;

Fig. 5 is a top plan view of the structure shown in Figs. 1-3 inclusive as viewed in a direction at right angles to the planes of the magazines, the magazines being in the position shown in Fig. 1.

Similar parts are designated by the same reference characters in the several views.

The preferred embodiments of the invention are shown in the accompanying drawings and will be hereinafter described in detail. It will be understood, however, that the invention is not restricted necessarily to the precise construction and arrangement shown, as equivalent constructions within the scope of the annexed claims are contemplated and will be included thereby.

In the present instance, the invention is shown as applied to a typographical machine of the well known linotype class which comprises a column 1 which is a part of the main frame of the machine and a distributor bracket 2 which is fastened rigidly to the column 1 and has two upwardly projecting arms which support at their upper ends the distributor beam 3, the distributor bar 4 being mounted on the beam 3 and a set of three distributor screws 5 being ordinarily used to feed the matrices M along the distributor bar 4 whereby the matrices are returned to their respective channels of the appropriate magazine.

According to the present invention a rocker frame is provided which is rotatable in a direction forwardly and rearwardly of the machine and about an axis which is fixed with respect to the main frame and the rocker frame to carry the magazines from an operative position relatively to the keyboard-controlled matrix delivery means to a position for removal of the magazines and vice versa, and this rocker frame also carries means for shifting the magazines bodily to bring any selected magazine into operative relation with the keyboard-controlled matrix delivery means. In the present instance a rock shaft 6 is provided which is stationary and is supported at its ends by rigid arms which are fixed to and project downwardly and forwardly from the

distributer bracket 2. A rocker frame 7 composed of two side plates 7^a and 7^b, which are rigidly connected to one another by suitable cross members, is mounted to rotate on the shaft 6 as an axis, this shaft 6 being in fixed relation to the rocker frame and to the main frame of the machine. The rocker frame has two outwardly and upwardly extending lugs 7^c toward its front end which are adapted to rest upon the top of a relatively fixed bracket 8 which latter forms a part of the main frame of the machine. A pair of parallel shafts 9 and 10 are mounted to rock in the frame 7, a pair of levers 11 and 12 of bell-crank form being keyed or otherwise fixed on or adjacent to the right-hand ends of said shafts, while a pair of levers 13 and 14 having single arms are keyed or otherwise fixed on or adjacent to the left-hand ends of said shafts. Two pairs of side plates 15 and 16 and 17 and 18 are pivotally connected to the upwardly-extending arms of the levers 11 and 12 and 13 and 14 respectively, each pair of side plates being rigidly secured to the respective sides of a pair of magazine frames 19 and 20, the side plates serving to hold the magazine frames together rigidly and in proper relation to one another. The magazine frames 19 and 20, as shown, are in superposed relation and preferably lie in planes which are parallel or substantially so, and they are preferably inclined downwardly and toward the front of the machine to cause the matrices to feed through and from the magazines by gravity under the control of the well known or any suitable escapement mechanism. The side plates 15 and 16 are provided with downwardly directed positioning lugs 15^a and 16^a which are adapted to rest upon surfaces appropriately positioned on the rocker frame 7, the surface on the rocker frame engaging the lug 15^a, which is preferably shouldered, as shown, in order that this lug will be positioned both vertically and in a direction lengthwise of the magazines, while the lug 16^a may position the rear portions of the magazine frames in a vertical direction or a direction at right angles to the planes of the magazine frames. The lugs 15^a and 16^a together with their co-operating supporting surfaces on the rocker frame are preferably duplicated on the left-hand side of the machine.

As previously stated, one arm of each of the bell-cranks 11 and 12 is connected to the respective side plate 15 or 16. The other arms of the bell-crank levers 11 and 12 are arranged at an angle to the arms first mentioned, (an angle of 90° being preferable) and these arms of the bell-cranks are pivotally connected to the ends of a link 21. By this construction the bell-crank levers 11 and 12 are operatively connected

by the link 21 and also by the magazine frames 19 and 20 through the medium of the side plates 15 and 16 which are operatively connected to the other arms of said bell-crank levers, with the result that the rock shafts 9 and 10 are connected to rotate in unison. A hand lever or other appropriate operating member 22 is provided for rotating the shafts 9 and 10 to shift the magazine frames for a purpose which will hereinafter appear. In the present instance the hand lever 22 has a laterally projecting handle 22^a, and the lever is connected to the forward shaft 9 in such a way that it can be disconnected therefrom when desired. In the present instance a key 23 is provided, this key being fitted into a keyway formed in the shaft 9 and is pivotally connected to said shaft by a pivot pin 23^a. A coiled spring 23^b acts normally to force the key out of its keyway and into a key-slot formed in the hub of the operating lever 22. The outer surface of this key is tapered in order that it will occupy a position wholly within the circumference of the shaft when the key is depressed or forced into the keyway against the action of the spring 23^b, the hand lever 22 being then free to rotate the shaft. A lip on the outer end of the key 23 provides a handle or finger-piece whereby it may be depressed, and this lip also engages the outer side of the hub of the hand lever and prevents the latter from sliding off the end of the shaft. Normally, however, the spring 23^b holds the key in the key-slot in the hub of the hand lever 22 and thereby forms an operative connection between said lever and the shaft 9.

The magazine frames 19 and 20 support two magazines 24 and 25, a cross-bar on the upper side of each magazine resting against the respective posts 24^a and 25^a which project upwardly from the magazine frames. In the construction shown in Fig. 1 each magazine carries a set of escapements 24^b and 25^b for controlling the delivery of matrices from the magazines. Either of these sets of escapements are adapted to be actuated by the vertically movable reeds or bars 26 which latter may be actuated in the usual or any suitable way under the control of the keyboard. In Fig. 1 the lower magazine 25 is shown in operative position with respect to the matrix delivery means, the actuating bars 26 being in position to operate the set of escapements 25^b of the lower magazine 25. With the lower magazine 25 in operative position as shown in Fig. 1, the hand lever 22 extends to the front of the machine, and when it is desired to place the upper magazine 24 in operative position relatively to the escapement actuating bars or matrix delivery means the hand lever 22 is swung upwardly and rearwardly to the position shown in

Fig. 2. The pivotal connections between the levers 11 and 12 and the side plates 15 and 16 of the magazine frames pass or rotate through arcs of circles concentric with the shafts 9 and 10 and all points of the magazines move through the same arcs. The first part of this movement is in an upward direction which carries the escapements of the magazine 25 up and away from the actuating bars 26, the next part of the movement being in a generally rearward direction which will carry the magazines 24 and 25 rearwardly, the forward end of the lower magazine 25 passing over and clear of the upper ends of the actuating bars 26, and the latter part of the movement of the magazines is in a downward direction which lowers the escapements 24^b of the upper magazine 24 into operative relation with the actuating bars, this movement being such as to avoid any conflict between the forward ends of the magazines and the escapement actuating bars 26. During this movement of the magazine frames, the magazine frames serve as a driving link when the link 21 is below the centers of the shafts 9 and 10, while the link 21 serves as a driver when the pivot points of the magazine frames are below the centers of the shafts, as shown in Fig. 2.

The magazine frames are provided with lugs 15^b and 16^b which come into position on the supporting surfaces of the rocker frame 7 when the upper magazine is brought into operative position. The parts are shown in this position in Fig. 2. These lugs serve as stops to prevent further rotation of the shafts 9 and 10 and they also operate to locate the magazine frames correctly in both parallel and perpendicular directions relatively to the planes of the magazines, thereby compensating for any inaccuracy of workmanship or spring or yield of the parts which move the frames.

A channel entrance 27 is provided at the upper end of the operative magazine, it embodying guides or partitions which control the fall of the matrices M from the distributor bar 4 into the respective channels 50 of the magazine. Obviously, the entrance 27 must be moved away from the path of the magazines when they are shifted out of operative position. To accomplish this the channel entrance is mounted on a frame 28 which latter is pivoted at each end on pins 28^a mounted on rearwardly projecting arms of the distributor bracket 2. The entrance frame 28 is connected by a link 29 to the hand lever 30, the latter being pivotally mounted at the front of the machine and, as shown, it is mounted on the bracket 8. Rearward motion of the hand lever 30 from the operative position shown in Fig. 1 throws back the entrance 27 from the position shown in Fig. 1 to the position shown

in Fig. 3, the entrance being then clear of the path of the shifting magazine, and the entrance can be returned to its normal operative position by a forward pull on the hand lever 30 after the desired magazine has been brought into operative position.

An advantageous feature of the present invention is that a single matrix distributor can be used for distributing matrices to the different magazines that are in use upon the machine. By providing means which shifts the plural magazines bodily to carry any desired magazine into co-operative relation with the escapement actuating bars or matrix delivery means, the upper ends of the magazines are shifted in unison with the lower or matrix delivery ends of the magazines, and the same movement which carries a magazine into operative relation with the matrix delivery means brings the upper or matrix receiving end of this particular magazine into co-operative relation with the distributor. Where, as in the present instance, the bodily shifting movement of the magazines is in an arcuate or circular path, the channel entrance which is located between the distributor and the upper end of the magazine which is in use is swung rearwardly by a conveniently operative connection which extends to the front of the machine, and in this way the channel entrance is swung into a position to clear the upper ends of the magazines while one is being shifted out of operative position and another is being shifted into operative position relatively to the matrix delivery means.

In order to prevent accidental spilling of matrices from the magazines when the latter are swung rearwardly or into position for removal, a shutter 31 is provided which normally closes the upper or matrix-receiving end of each magazine, each shutter being connected to its respective magazine by relatively long flat springs 31^a. A shutter opening device 32 is pivotally mounted on each magazine frame, each opening device having a pin 32^a which is adapted to strike against a stationary cam plate 33 secured to the distributor bracket 2 at the respective side of the magazine. Preferably, one of these shutter opening devices is provided at each side of the magazine and duplicate cam plates 33 are provided. Engagement of the pins 32^a with the cam plates 33 operates to swing the shutter opening devices rearwardly and thereby depress and move the shutters into open position. This engagement, however, terminates when the respective magazine is moved out of operative position, either by the shifting of the hand lever 22, or by the rearward rocking of the entire rocker frame 7 which rotates the magazine frames and magazines bodily in a rearward direction. By this construction the shutters are automatically opened

when the respective magazines are brought into operative position while they are closed at all other positions of the respective magazines.

- 5 A tray 34 is preferably provided for the purpose of catching any matrices which may fall from the distributor when the entrance is open to remove any matrices which may have become wedged between the entrance and the guides. It is preferable that the tray should always maintain a level position in order to avoid spilling of the matrices therefrom, irrespective of the position of the rocker frame 7 about its axis 6.
- 10 In the present instance the tray is loosely swung upon the shaft 10 by the hinges 35 and the hinges are connected by a link 36 to a bracket 37, the latter being fastened to the distributor bracket 2. The pivot pins 15 of the link 36 are so placed that the distance between the upper pin and the center of the shaft 10 is equal to the distance between the lower link pin and the center of the shaft 6, a parallel motion being thereby 20 provided whereby the tray 34 will always maintain a level or horizontal position, irrespective of the position of the rocker frame 7 about its axis 6.

Instead of the magazines carrying their 25 own sets of escapements, as in the construction described above, a single set of escapements 38 may be arranged in fixed relation on the main frame of the machine, in which case these escapements will always remain 30 in coöperative relation with the actuating rods 39 controlled by the keyboard, and the lower or delivery ends of the upper and lower magazines 40 and 41 may be brought 35 into coöperative relation with the escapements, as shown in Fig. 1*. Substantially 40 the same mechanism may be used in connection with an arrangement such as that just described, the arcs shown in dotted lines indicating the movement of the magazines 45 which serves to remove one magazine from operative relation with the escapements and to bring the other magazine into operative relation therewith.

One of the important advantages of this 50 invention is that it enables the escapements to be acted upon directly by the actuating bars 26, there being no intermediate connections such as are used in other constructions where plural shiftable magazines are employed.

Another valuable feature is the simple 55 movement involved, the freedom from complication, and the strength of the magazine supporting and shifting means. Also, it is 60 to be noted that while the magazines travel through considerable distance, the vertical lift required is comparatively small and, therefore, the relatively heavy weight which has to be shifted can be readily done by the 65 manually operated lever.

Still another important feature is the combined supporting frame for the magazines which enables the magazines to be shifted by one movement and swung back for removal by an entirely independent 70 movement.

I claim as my invention:—

1. The combination of a main frame, matrix delivery means thereon, and a magazine carrying frame having a plurality of magazines mounted in fixed relation therein, both ends of the magazine carrying frame being movable about different axes relatively to the main frame by a single circular movement through which the frame carrying the 80 magazines is caused to adjust either magazine in operative position relatively to the matrix delivery means.

2. In a machine of the linotype class embodying a main frame and matrix delivery 85 means thereon, a magazine carrying frame having a plurality of inclined magazines mounted in fixed relation thereon, the magazine carrying frame being bodily movable in an arcuate path to remove one magazine 90 from operative position relatively to the matrix delivery means and to bring another magazine into operative position relatively to the matrix delivery means, and means for maintaining the magazines at a fixed or constant angle of inclination during such shifting of the magazines.

3. In a machine of the linotype class embodying a main frame and matrix delivery means, the combination of a plurality of inclined magazines adapted to receive matrices at their upper ends and to discharge matrices at their lower ends, a frame for holding the magazines in constant relative position to one another, and means coöperative with 100 said magazine frame for moving the matrix receiving and delivery ends of the magazines in arcs about parallel axes, such movement of the magazine frame carrying one magazine 105 out of coöperative relation with the matrix delivery means and carrying another magazine into coöperative relation therewith.

4. The combination of a main frame, matrix delivery means, a magazine carrying 115 frame having a plurality of magazines mounted in fixed relation therein, and means for moving the magazine carrying frame bodily relatively to the matrix delivery means in a direction first upwardly, then 120 in a direction forwardly or rearwardly, and thence downwardly.

5. The combination of a main frame, matrix delivery means thereon, a magazine carrying frame having a plurality of magazines mounted in fixed relation therein, and means for moving the magazine carrying frame bodily in an arcuate path relatively to the matrix delivery means about parallel 125 axes to bring the different magazines into 130

- operative position relatively to the matrix delivery means.
6. The combination of a main frame having escapement actuating means thereon, a magazine carrying frame having a plurality of magazines mounted in fixed relation therein, a pair of rock shafts located toward the front and rear of the magazines, and means connecting said rock shafts to the magazine carrying frame and operative to swing the same bodily in an arcuate path to bring either of the magazines into a given position relatively to the escapement actuating means.
- 18 7. The combination of a main frame having escapement actuating means thereon, a magazine carrying frame having a plurality of magazines mounted in fixed relation therein, a pair of rock shafts located toward the front and rear of the magazines, and a parallel motion connection between said shafts and the magazine carrying frame operative to bring the magazines alternately into a given operative position relatively to the escapement actuating means by swinging and reciprocating action.
- 30 8. The combination of a main frame having escapement actuating means thereon, a magazine carrying frame having a plurality of magazines mounted therein, and a parallel motion connection between the main frame and the magazine carrying frame for supporting the latter and the magazines and operative to remove one magazine from operative relation with said escapement actuating means, shift the magazines bodily in a substantially endwise direction, and bring another magazine into operative relation with said escapement actuating means.
- 40 9. The combination of a main frame having escapement actuating means thereon, a magazine carrying frame having a plurality of magazines mounted therein, a pair of rock shafts, arms thereon pivotally connected to the forward and rear portions of the magazine carrying frame, arms, on said shafts at an angle to the arms first mentioned, and a link pivotally connecting the latter arms.
- 50 10. In combination, a main frame, a supplementary frame movably mounted on the main frame, a magazine carrying frame movably mounted on the supplementary frame, a plurality of removable magazines mounted on said carrying frame and having a constant relative position to each other, and means for moving the carrying frame on the supplementary frame to bring any magazine into operative position, the supplementary frame being movable on the main frame to bring the magazines into position for removal.
- 60 11. In a machine of the linotype class embodying a main frame and matrix delivery means thereon, the combination of an inclined magazine shiftable to and from co-operative relation with said matrix delivery means by movement of the magazine bodily in an arcuate path, a distributor situated above and behind said magazine, a movable entrance between the magazine and distributor, and means for moving the entrance to clear the magazine during the arcuate shifting movement thereof.
- 75 12. In a machine of the linotype class embodying a main frame, escapement actuating means thereon, and a single matrix distributor thereon, the combination of a magazine carrying frame movable bodily in an arcuate path to carry its lower matrix discharging end to and from co-operative relation with the escapement actuating means and to simultaneously carry its upper matrix receiving end to and from co-operative relation with said distributor, and an entrance having means for moving it to and from operative position between the distributor and the upper matrix receiving end of the magazine.
- 80 13. In a line casting machine, in combination, a frame having mounted thereon a plurality of inclined parallel magazines, any one of which may be placed in operative position, a series of escapement actuating members underlying the lower end of the operative magazine, means for swinging the lower end of the magazine carrying frame in a substantially circular path to cause the magazines to clear said actuating members when changing operating position, and connected means for moving the upper end of the carrying frame in a similar path.
- 85 14. In a line casting machine, the combination with a plurality of parallel inclined magazines of equal length, each magazine having a series of escapements underlying its lower end and having a shutter mounted upon it and operative to open and close its upper end, of a main frame, a magazine carrying frame movable to bring any magazine thereon into operative position, a series of escapement actuating members, and joint means to swing the lower end of the magazine carrying frame in a circular path to clear the escapement actuating members and to swing the upper end of the magazine carrying frame in a similar path to operate the magazine shutters.
- 90 15. In testimony whereof I have hereunto set my hand in presence of two subscribing witnesses.
